UNITED STATES PATENT OFFICE.

CALEB A. LIBBY, OF EVANSVILLE, WISCONSIN, ASSIGNOR OF ONE-HALF
TO MARTIN V. PRATT, OF SAME PLACE.

SPRING-BED.

SPECIFICATION forming part of Letters Patent No. 234,303, dated November 9, 1880.

Application filed April 29, 1880. (Model.)

To all whom it may concern:

Be it known that I, CALEB ANCIL LIBBY, a citizen of the United States, residing at Evansville, in the county of Rock and State of Wisconsin, have invented a new and useful Improvement in Spring-Beds, of which the following is a specification.

The object of my invention is to furnish a cheap, durable, easy, wood-spring bed, which may be raised at the head, also easily reversed, thereby keeping it in the best possible shape. I attain these objects by the mechanism illustrated in the accompanying drawings, in which—

15 Figure 1 is a surface view of the entire bed. Fig. 2 is a side view, showing one side spring, the bolster, and the manner of raising and lowering the head of the bed. Fig. 3 is an end view, showing one end spring, bolster, and slide on end of slats.

Similar letters refer to similar parts throughout the several views.

In the drawings, A is a cross-piece at what is termed the "head" of the bed. B is a similar cross-piece at the foot of the bed. The ends of said cross-pieces rest on the sides of the bedstead, thereby supporting the entire bed in the bedstead.

C is a slat running lengthwise in the center 30 of the bed, fastened on the under side of cross-pieces A B at the points a a.

D is a spring running horizontal, with cross-pieces A B on the under side of the same, fastened in the center at the points a a. Both 35 ends are similarly constructed in this respect.

E E are side springs running lengthwise of the bed, resting on the ends of the end springs, D D, at the points b b.

F F and G G are a series of slats, which 40 may be increased or diminished in number and length to accommodate different-sized bedsteads, slit lengthwise or not, as preferred. The ends c c are secured in place by the cross-pieces H H. The entire series is kept in place 45 on the cross-piece B by the pins d d, and may be taken up and reversed all together. The ends e e of this series of slats are kept in place and allowed to spring independently by means of a slide constructed as follows:

Two cross-pieces, I I, are fastened at the 50 ends to slats F F, having blocks f f between the slats. This slide can be moved to different points by removing the fastenings and then sliding the piece I to or from the end of the slats and securing it at the changed 55 position, thus altering the spring of said series of slats at pleasure.

J is a cross-piece running either over or under the slat C, with its ends resting on the side springs, E E, at the points g g, and, being 60 movable, can be used to change the spring of the bed.

K is what is termed the "bolster," on which rests one end of the slats F F G G.

L L are standards passing loosely through 65 cross-piece J, the upper ends being secured to the bolster K. Holes are formed in the standards, through which are passed pins, which can be removed from one set of holes and passed through another, thereby adjusting the 70 bolster higher or lower, as desired. If desired, the pins of one standard only may be changed, thereby raising or lowering one side only, and consequently making one side higher than the other.

Having thus described my invention and mode of operating it, I claim as new therein and my invention—

1. In a bed-bottom, the side springs, E, perforated near the bolster K, as shown, combined 80 with the vertically and horizontally adjustable bolster K, side slats, F, and intermediate slats G, admitting of longitudinal play, as set forth, substantially as and for the purposes described.

2. In a bed-bottom, the side springs, E, and end springs, D, in combination with side slats, F, secured to strips H and I, intermediate slats G, secured at one end to strip H and allowed a free longitudinal but a limited lateral 90 play at the other end in the strip I, and vertically-adjustable bolster K, substantially as and for the purpose set forth.

CALEB ANCIL LIBBY.
